Application December 30, 1947, Serial No. 794,560

15 Claims. (Cl. 123—127)

1

The present invention relates to a fuel supply system and more particularly to a carburetor for an internal combustion engine adapted to operate under certain conditions on less than the full number of cylinders. This type of engine is illustrated in my copending application Serial No. 751,282, filed May 29, 1947, and will be referred to hereinafter as a "split engine." Some of the cylinders of the split engine, for example three cylinders of a six cylinder engine, are in operation throughout the entire time the engine is in operation, while the remaining cylinders may be in operation only during starting, power pick-up and high power output. For convenience of description, the running of the engine on the full number of cylinders will be referred to as "standard engine operation" and the running of the engine on only a part of the cylinders as "split engine operation." The cylinders which are in continuous operation will be referred to as "standard cylinders" and those which are in operation only during starting, power pick-up and high power output as "power cylinders." In the split engine disclosed in my copending application, the power cylinders are rendered inoperative by the closing of the inlet and exhaust valves in response to variations in one or more engine operating conditions, such as manifold vacuum, vehicle speed, engine temperature and throttle position. During split engine operation, the pistons of the power cylinders, while continuing to reciprocate, do not expel the exhaust gases contained in their respective cylinders, nor do said cylinders receive new charges of fuel-air. In this arrangement, either a single intake manifold for all the cylinders of the engine or two separate manifolds, one for the standard cylinders and the other for the power cylinders, may be used.

One of the principal objects of the present invention is to provide a carburetor for a split engine which will supply the proper fuel-air ratio to said engine throughout its entire range of operation.

Another object of the invention is to provide a carburetor for a split engine wherein the supply of fuel-air mixture is automatically adjusted for standard or split engine operation as the engine shifts between said operations.

Another object of the invention is to provide a device in combination with the aforementioned carburetor for adjusting a spark advance mechanism to standard and split engine operations.

Additional objects and advantages will appear from the following description and accompanying drawings wherein one embodiment of my invention is disclosed. The invention may be in

combination with either a single or a double barrel carburetor and is not limited to any particular type of split engine, but is understood to be generally applicable to any of said engines wherein the control of the power cylinders includes a means posterior to the fuel supply nozzle for interrupting the flow of air through the carburetor to the power cylinders for rendering said cylinders inoperative. My invention may be more fully understood by referring to the accompanying drawings, wherein:

Figure 1 is a side elevation of a multiple cylinder internal combustion engine embodying the present invention;

Figure 2 is a schematic view of the carburetor, showing the various elements rearranged to more clearly illustrate their operative relationship to one another;

Figure 3 is a sectional view taken on line 2—2 of Figure 2;

Figure 4 is a top plan view of the carburetor;

Figure 5 is a side elevation of the carburetor;

Figure 6 is a detailed sectional view of the power enrichment jet and the valve control mechanism therefor;

Figure 7 is a detailed sectional view of the accelerating pump; and

Figure 8 is a detailed view of the idle system, showing the induction passage of the carburetor in cross-section.

The present invention may be readily understood by referring to the accompanying drawings in which Figure 1 shows a multiple cylinder internal combustion engine in combination with the present engine control mechanism wherein numeral 1 designates a carburetor, 2 a spark advance mechanism, 3 a vacuum actuated switch for the split engine control, 4 a manually actuated switch for said control, 5 a speed responsive switch for said control, 6 a temperature responsive switch, and 7 a tappet assembly for controlling the operation of a portion of the cylinders, said tappet assembly being actuated by a solenoid mechanism 8 in response to the aforementioned control switches. The several switches are connected by leads to relays in box 9 which in turn control solenoid mechanism 8. With the exception of the mechanism for rendering a portion of the cylinders inoperative and the control system for said mechanism, the present engine is a conventional multiple cylinder internal combustion engine. The one shown in Figure 1 is a six cylinder, L head motor with poppet-type valves, in which three of the cylinders may be rendered inoperative.

Referring to Figure 2, numeral 10 designates

Referring to Figure 2, numeral 10 designates

the induction passage of the carburetor, 12 the air inlet, 14 the mixture outlet, 15 a choke valve, and 16 a throttle valve, said throttle valve being mounted on a throttle valve shaft 18 journaled in the throttle body of the carburetor. The fuel is discharged into the induction passage at the throat of venturi 20 through discharge nozzle 22 which communicates with a fuel bowl 24 through fuel well 26, a main fuel conduit 28 and the main fuel metering jet 30 disposed in one end of said conduit adjacent the bottom of fuel bowl 24. The fuel well includes a sleeve 40 having several small holes 42 uniformly spaced over the surface thereof and four large fuel orifices 44 near the bottom end thereof on a plane with conduit 28. The sleeve 40 is spaced from the internal wall of the well to permit air to surround the sleeve and pass through holes 42 into the internal portion of said sleeve. Air is admitted into well 26 from the air intake end 12 of the induction passage through port 50 and is metered at orifice 52 as it passes downwardly through passage 54 into the annular space between sleeve 40 and the side wall of the well. In this construction, the fuel flows from bowl 24 through metering orifice 30, conduit 28 and holes 44 into sleeve 40 and passes upwardly through said sleeve where it forms an emulsion with the air admitted from the annular space about the sleeve through holes 42. The fuel-air emulsion is then discharged through nozzle 22 into the throat of the venturi 20. A conventional fuel inlet valve and float mechanism for controlling the operation of said valve are shown at numerals 60 and 62, respectively.

The construction of the fuel discharge nozzle may be more fully understood by referring to Figure 8 wherein another cross-sectional view is shown. It is seen that nozzle 22 discharges the fuel adjacent the under side of a horizontal bar 48 formed integrally with venturi 20. The fuel discharge end of the nozzle is provided with a downwardly tapering ear 49 which prevents the fuel from flowing along the under side of said nozzle to the venturi and thence down the side wall of the induction passage. A similar ear 51 is disposed on the opposite side of the venturi under bar 48. Novel features of the fuel discharge system shown in Figures 2 and 8 are claimed in a divisional application Serial No. 293,730, filed June 16, 1952 and in my copending application Serial No. 8,951, filed February 17, 1948.

To provide an increased quantity of fuel for standard engine operation, main fuel conduit 28 is connected with the fuel bowl by an auxiliary metering jet 70 disposed downstream from jet 30. This auxiliary jet 70 is controlled by a valve 72 urged to its closed position for split engine operation by spring 74 and to its open position for standard engine operation by a reciprocable rod 76 moved in the direction to open said valve by a spring 78 reacting between plate 80 secured to the lower end of said rod and an external shoulder 82 on bushing 84. When rod 76 is in its lowermost position, valve 72 is held open so that the fuel will flow through jet 70 into the valve sleeve and thence through a plurality of orifices 86 into conduit 28. The means for actuating rod 76 will be described more fully hereinafter.

A power enrichment jet 90 connects the fuel bowl with the main fuel conduit 28 posterior to the main jet 30 and auxiliary fuel jet 70 and is controlled by a valve 92 urged to its closed position by a spring 94. Valve 92 is operated by a

reciprocable rod 96 which is urged in the direction to open said valve by a spring 98 reacting between a plate 100 secured to the lower end of said rod and a plate 102 near the upper end thereof. Rod 96 is secured to and actuated by a piston 104 mounted in a cylinder 106 which is connected at its upper end by a conduit (not shown) with the induction passage on the engine side of throttle valve 16.

A manually actuated accelerating pump generally shown at 110 consists of a cylinder 112, a piston 114 and a lever 116 connecting the upper portion of said piston 114 with the throttle valve actuating mechanism 118 mounted on the left-hand end of shaft 18, as shown in Figure 2. The upper end of lever 116 is disposed in a slot 120, as shown in Figure 7, and is yieldably urged toward the upper end of piston 114 by a spring 122 reacting between the lower internal end of piston 114 and the under side of a lever support 124, thus providing a follow-up arrangement for piston 114 in discharging fuel from cylinder 112. When the piston 114 is raised, fuel flows from the fuel bowl into the lower portion of cylinder 112 through a valve controlled orifice 126, and as the piston is moved downwardly on the opening movement of the throttle valve, the fuel discharges from the lower end of cylinder 112 through conduit 128 and discharge orifice 130 disposed near the throat of venturi 20. An air duct 132 connects the upper end of conduit 128 with the induction passage 10 above venturi 20 to break the effect of Venturi vacuum on the fuel in conduit 128. A ball 134 of a ball check valve 35 is disposed in an enlarged portion 135 of conduit 128 and is adapted to seat over the fuel inlet of the enlarged portion when the accelerating pump is inoperative and to seat over air inlet, i. e. the lower end of duct 132, when fuel is being discharged from the accelerating pump. The ball 134 thus permits air to bleed through the pump discharge orifice when the pump is not in operation and prevents the suction in the throat of the venturi from drawing fuel from the pump cylinder. During the operation of the pump, the ball 134 seats over the lower end of duct 132 and prevents the fuel from being discharged by the accelerating pump through duct 132.

A conduit 140 connects the spark advance mechanism 2 with the induction passage on the engine side of the throttle valve. A duct 142 is adapted to bleed air into conduit 140 during split engine operation and thus lower the effect of manifold vacuum in the spark advance mechanism. The duct 142 is controlled by a valve 144 mounted in valve sleeve 146 and urged to its closed position over orifice 147 by a spring 148. The valve 144 is actuated by a reciprocable rod 150 mounted in a bushing 152 and urged in the direction to open said valve by a spring 154 reacting between a plate 156 secured to the lower end of said rod and an external shoulder on bushing 152.

The idle system of the carburetor, which is best shown in Figure 8, consists of two vertically arranged conduits 160 and 162 which connect the lower portion of well 26 adjacent holes 44 with idle discharge ports 164 and 166 above and below throttle valve 16, respectively. A bleed 168 having an orifice 170 is provided to admit air into the system for forming an emulsion with the fuel as it enters conduit 162. When the throttle valve is in closed or nearly closed position, fuel flows from well 26 through conduits 160 and 162 and after mixing with air admitted through

the idle air bleed 168, discharges through port 166. Additional air is bled into the idle air system at port 164 when the edge of throttle valve 16 is below said port. As the throttle valve is opened and the edge thereof passes above port 164, fuel discharges through both ports 164 and 166, thus providing additional fuel for the increased flow of air. An idle adjustment valve 172 controls the quantity of fuel-air emulsion discharged through port 166.

During split engine operation, the power enrichment valve 92, the auxiliary valve 72 and air bleed valve 144 are held in the position shown in Figure 2, i. e. all three valves are held in closed position. The actuating rods 96, 76 and 150, for these valves respectively, are controlled by a solenoid 180 (Figures 4 and 5) through a lever 182 and a rotatable shaft 184 having mounted thereon levers 185, 186, 187 and 188 for the power enrichment valve, auxiliary valve, spark advance valve, and accelerating pump, respectively. When the solenoid is actuated, lever 182 moves to the right, as shown in Figure 5, rotating shaft 184 a part turn in the clockwise direction, lifting levers 186 and 187 which in turn lift rods 76 and 150, thus permitting valves 72 and 144 to close. In the clockwise movement of shaft 184 and lever 185, stem 189 moves axially until the free end thereof projects into cylinder 106 under piston 104, as shown in Figure 6, and prevents rod 96 from opening valve 92 of the power jet when the manifold vacuum becomes too low to retain piston 104 in the upper end of cylinder 106. A yieldable connection is provided on stem 189 to permit continued operation of the levers on shaft 184 should stem 189 be prevented from moving by the presence of piston 104 in the lower end of cylinder 106. A stem 194 operated by lever 188 is similar in construction and operation to stem 189 and is provided for the purpose of limiting the stroke of the accelerating pump during split engine operation to less than that during standard operation.

During standard operation of the engine, solenoid 180 is de-energized, thus permitting spring 78 of the auxiliary fuel jet and spring 154 of the spark advance mechanism to open valves 72 and 144, respectively. Thus, fuel flows through main fuel metering jet 30, auxiliary fuel jet 70 and conduit 28, into well 26. Since the manifold vacuum is somewhat greater for any given speed when all the cylinders are operating than when only a part of the cylinders are operating, the effect of said vacuum on the spark advance mechanism must be modified if the mechanism is to operate satisfactorily during split engine operation. Thus, valve 144 is held open during standard engine operation to admit air into conduit 140 and thus decrease the vacuum transmitted from the induction passage to the spark advance mechanism. In standard operation, the accelerating pump and power enrichment jet operate as in conventional carburetors, i. e. the accelerating pump piston moves through a full stroke when the throttle valve is moved from closed to wide open position, and the power enrichment jet is opened whenever the manifold vacuum falls below a predetermined value enabling spring 98 to move rod 96 in the direction to open power enrichment valve 92.

When the engine shifts from standard to split engine operation, the solenoid 180 is energized, moving lever 182 to the right, as shown in Figure 5, and rotating shaft 184 in a clockwise direction, thus lifting rod 76 of the auxiliary jet

and rod 150 of the spark advance bleed to permit valves 72 and 144 to close. With the closing of valve 72, the quantity of fuel delivered to the main discharge jet is adjusted to that required for split engine operation. With the closing of valve 144 of the spark advance mechanism, the full effect of manifold vacuum is transmitted to the spark advance mechanism. In most split engine operations, it has been found that the pulsations of the engine running on a relatively small number of cylinders cause the fuel-air mixture to become richer so that no enrichment mechanism such as jet 90 is required for high power output. Thus, when solenoid 180 is energized in the shift to split engine operation, stem 189 moves under piston 104 so that spring 98 cannot lower rod 96 and open the power enrichment valve 92 when the manifold vacuum is decreased below a predetermined value. Also, when the solenoid is energized, stem 184 moves into the path of a shoulder on the upper portion of piston 104, thus preventing the piston from completing its full stroke. The yieldable connection between lever 188 and piston 104, however, permits the throttle valve to move to its wide open position.

While only one embodiment of the invention has been described herein, there are certain conditions in which a rearrangement of the elements comprising the carburetor may be desirable, for example, when the carburetor is used on an engine having a large number of cylinders, the pulsations of the standard cylinders in split engine operation may not be of sufficient magnitude to materially enrich the fuel; therefore, the operation of the power enrichment jet 90 for split engine operation may under certain circumstances, be desirable. Many other changes may be made in the construction of the present carburetor to suit requirements.

I claim:

1. A carburetor for a split engine comprising an induction passage, a throttle in said induction passage, a means for manually actuating said throttle, a main fuel discharge jet, a fuel bowl, a fuel conduit connecting said discharge jet with said fuel bowl, a main fuel metering orifice in said conduit and an auxiliary fuel metering orifice connecting said fuel bowl with said conduit posterior to said main metering orifice, a valve for controlling said auxiliary orifice, a power enrichment orifice connecting said fuel bowl with said conduit posterior to said main metering orifice, a fuel valve for controlling said power enrichment orifice, a vacuum controlled member for opening said power enrichment valve, an accelerating pump being yieldably connected to the throttle actuating means, a passageway for transmitting manifold vacuum to a spark advance mechanism, a duct for bleeding air into said passageway to lessen the effect of said vacuum on said mechanism, a valve for controlling said duct, and an electrically actuated means so constructed and arranged as to open said auxiliary and duct valves for standard engine operation and to close said valves, prevent actuation of said vacuum controlled member of the power enrichment valve and limit the stroke of said accelerating pump for split engine operation.

2. A carburetor for a split engine comprising an induction passage, a throttle in said induction passage, a main fuel discharge jet, a fuel bowl, a main fuel conduit connecting said discharge jet with said fuel bowl, a main fuel metering orifice in said conduit, an auxiliary fuel metering

orifice connecting said fuel bowl with said conduit posterior to said main metering orifice, a valve for controlling said auxiliary orifice, a power enrichment orifice connecting said fuel bowl with said conduit posterior to said main metering orifice, a valve for controlling said power enrichment orifice, a vacuum controlled member for opening said power enrichment valve, an accelerating pump yieldably connected to a means for actuating said throttle valve, a passageway for transmitting manifold vacuum to a spark advance mechanism, a duct for bleeding air into said passageway to lessen the effect of said vacuum on said mechanism, a valve for controlling said duct, and a means so constructed and arranged as to open said auxiliary and duct valves for standard engine operation and to close said valves, prevent actuation of the vacuum controlled member of the power enrichment valve, and limit the stroke of said accelerating pump for split engine operation.

3. A carburetor for a split engine comprising an induction passage, a throttle in said induction passage, an actuating means for said throttle, a main fuel discharge jet, a fuel bowl, a main fuel conduit connecting said discharge jet with said fuel bowl, a main metering orifice in said conduit, an auxiliary fuel metering orifice connecting said fuel bowl with said conduit posterior to said main metering orifice, a valve for controlling said auxiliary orifice, a power enrichment orifice connecting said fuel bowl with said conduit posterior to said metering orifice, a valve for controlling said power enrichment orifice, a vacuum controlled member for opening said power enrichment valve, an accelerating pump yieldably connected to the throttle actuating means, and a means so constructed and arranged as to open said auxiliary valve for standard engine operation and to close said valve, prevent actuation of the vacuum controlled member of the enrichment valve, and limit the stroke of said accelerating pump for split engine operation.

4. A carburetor for a split engine comprising an induction passage, a main fuel discharge jet for delivering fuel to said induction passage, a fuel bowl, a main fuel conduit connecting said discharge jet with said fuel bowl, a main fuel metering orifice in said conduit, an auxiliary fuel metering orifice connecting said fuel bowl with said conduit posterior to said main metering orifice, a valve for controlling said auxiliary orifice, an accelerating pump, and a means so constructed and arranged as to open said auxiliary valve for standard engine operation and to close said valve and limit the stroke of said accelerating pump for split engine operation.

5. A carburetor for a split engine including a control means responsive to variations in at least one engine operating condition of the class consisting of manifold vacuum, speed, and throttle position for shifting the engine between standard and split operation, comprising an induction passage, a main fuel discharge jet, a fuel bowl, a main fuel conduit connecting said discharge jet with said fuel bowl, a main metering orifice in said conduit, an auxiliary fuel metering orifice connecting said fuel bowl with said conduit posterior to said main metering orifice, a valve for controlling said auxiliary orifice, and a means adapted to be controlled by said control means to open said auxiliary valve for standard engine operation and to close said valve for split engine operation.

6. A carburetor for a split engine comprising

an induction passage, a fuel bowl, a main fuel conduit connecting said induction passage with said fuel bowl, a main fuel metering orifice in said conduit, an auxiliary fuel metering orifice connecting said fuel bowl with said conduit posterior to said main metering orifice, a valve for controlling said auxiliary orifice, and an electrically actuated means so constructed and arranged as to open said auxiliary valve for standard engine operation, and to close said valve for split engine operation, said electrical means being energized in response to variations in at least one engine operating condition of the class consisting of manifold vacuum, speed, temperature and throttle position.

7. A carburetor for a split engine including a control means responsive to variations in at least one engine operating condition of the class consisting of manifold vacuum, speed, and throttle position for shifting the engine between standard and split operation, comprising an induction passage, a fuel bowl, a main fuel conduit connecting said induction passage with said fuel bowl, a main fuel metering orifice in said conduit, an auxiliary fuel metering orifice connecting said fuel bowl with said conduit posterior to said main metering orifice, a valve for controlling said auxiliary orifice, and a means adapted to be controlled by said control means for regulating said valve to obtain the desired fuel-air ratio for split engine operation.

8. A carburetor for a split engine comprising an induction passage, a fuel bowl, a main fuel conduit connecting said induction passage with said fuel bowl, a main fuel metering orifice in said conduit, an auxiliary fuel metering orifice connecting said fuel bowl with said conduit posterior to said main metering orifice, a valve for controlling said auxiliary orifice, a power enrichment orifice connecting said fuel bowl with said conduit posterior to said main metering orifice, a valve for controlling said power enrichment orifice, a member for opening said power enrichment valve, and means for regulating said auxiliary valve and said member for the power enrichment valve to obtain the desired fuel-air ratio for split engine operation.

9. A carburetor for a split engine having a control means for shifting the engine between standard and split operation, comprising an induction passage, a fuel bowl, a main fuel conduit connecting said induction passage with said fuel bowl, a main fuel metering orifice in said conduit, an auxiliary fuel metering orifice connecting said fuel bowl with said conduit posterior to said main metering orifice, a valve for controlling said auxiliary orifice, an accelerating pump, and a means responsive to the operation of said control means for regulating said valve and said accelerating pump to obtain the desired fuel-air ratio for split engine operation.

10. A carburetor for a split engine comprising an induction passage, a fuel bowl, a main fuel conduit connecting said induction passage with said fuel bowl, a main fuel metering orifice in said conduit, an auxiliary fuel metering orifice connecting said fuel bowl with said conduit posterior to said main metering orifice, a valve for controlling said auxiliary orifice, a power enrichment orifice connecting said fuel bowl with said conduit posterior to said main metering orifice, a valve for controlling said power enrichment orifice, a vacuum controlled member for opening said power enrichment valve, an accelerating pump, and a means for regulating said

auxiliary valve, said accelerating pump and said vacuum controlled member for the power enrichment valve to obtain the desired fuel-air ratio for split engine operation.

11. A carburetor for a split engine comprising an induction passage, a fuel bowl, a main fuel conduit connecting said induction passage with said fuel bowl, a main fuel metering orifice in said conduit, an auxiliary fuel metering orifice connecting said fuel bowl with said conduit posterior to said main metering orifice, a valve for controlling said auxiliary orifice, a passageway for transmitting manifold vacuum to a spark advance mechanism, a duct for bleeding air into said passageway to lessen the effect of said vacuum on said mechanism, a valve for controlling said duct, and a means so constructed and arranged as to open said valves for standard engine operation and to close said valves for split engine operation.

12. A carburetor for a split engine including a control means responsive to variations in at least one engine operating condition of the class consisting of manifold vacuum, speed, and throttle position for shifting the engine between standard and split operation, comprising an induction passage, a source of fuel, a conduit connecting said source with the induction passage, a metering means in said conduit, a valvular means for varying the capacity of said metering means, and means adapted to be controlled by said control means for regulating said valvular means to obtain the desired fuel-air ratio for split engine operation.

13. A carburetor for a split engine including a control means responsive to variations in at least one engine operating condition of the class consisting of manifold vacuum, speed, and throttle position for shifting the engine between standard and split operation, comprising an induction passage, a source of fuel, a conduit connecting said source with the induction passage, a metering means in said conduit, a valvular means for varying the capacity of said metering means, a power enrichment means connecting said source with the induction passage, a member for controlling said power enrichment means, and means adapted to be controlled by said control means for regulating said valvular means and said member to obtain the desired fuel-air ratio for split engine operation.

14. A carburetor for a split engine having a control means for shifting the engine between standard and split operation, comprising an induction passage, a fuel bowl, a conduit connecting said fuel bowl with the induction passage, a metering means in said conduit, a valvular means for varying the capacity of said metering means, an accelerating pump, and means responsive to the operation of said control means for regulating said valvular means and said accelerating pump to obtain the desired fuel-air ratio for split engine operation.

15. A carburetor for a split engine having a control means for shifting the engine between standard and split operation, comprising an induction passage, a fuel bowl, a conduit connecting said fuel bowl with the induction passage, a metering means in said conduit, a valvular means for varying the capacity of said metering means, a power enrichment means connecting said fuel bowl with the induction passage, a member for controlling said power enrichment means, an accelerating pump, and a means responsive to the operation of said control means for regulating said valvular means, said member and said accelerating pump to obtain the desired fuel-air ratio for split engine operation.
